UNITED STATES PATENT OFFICE.

ROY X. TUTTLE, OF BATTLE CREEK, MICHIGAN.

METHOD OF ADMINISTERING THERAPEUTIC LIGHT TREATMENTS.

1,395,065.

Specification of Letters Patent. Patented Oct. 25, 1921.

Application filed February 14, 1921. Serial No. 444,893.

To all whom it may concern:

Be it known that I, ROY X. TUTTLE, a citizen of the United States, residing at Battle Creek, county of Calhoun, State of Michigan, have invented certain new and useful Improvements in Methods of Administering Therapeutic Light Treatments, of which the following is a specification.

This invention relates to improvements in methods of administering therapeutic light treatments.

One of the objections or difficulties met in the prolonged application of light in its use for therapeutic effects is that the continuous heat congests the part treated and proper blood and lymph movement is interfered with thereby depriving the tissues of the healing and cleansing effects of frequent blood changes and, further, the treatment becomes so disagreeable and painful that the patient is likely to object and insist on the termination of the treatment.

Attempts have been made to avoid or overcome this by having an attendant rub the exposed surface or make applications of ice or subject the surface to a cold air blast. The first two methods require the constant service of an attendant; there is a lack of uniformity, and carelessness and want of skill on the part of the attendant has a very material bearing on the result of the treatment.

It is the main object of my invention to provide a method in which the therapeutic light treatments may be effectively administered and alternate heating and cooling produced to prevent congestion and insure frequent blood changes in the part to be treated and a treatment which is not painful.

Further objects will appear as the description proceeds.

In the accompanying drawing I illustrate an apparatus for carrying out my treatments by my improved method, in which:

Figure I is a detail side view of a thermostatic lamp, the patient being indicated conventionally, a thermal flasher being shown in operative relation to the lamp, and being shown partially in section on line 1-1 of Fig. II.

Fig. II is a detail view partially in section through the thermal flasher on a line corresponding to line 2-2 of Fig. I.

Fig. III is a diagrammatic view illustrating the wiring for the lamp and flasher.

In the drawing similar reference characters refer to similar parts throughout the several views, and the sectional views are taken looking in the direction of the little arrows at the ends of the section lines.

In practising my improved method of treatment an electric lamp, as 1, provided with a suitable reflector is directed against the part to be treated. The efficiency of light treatment has been demonstrated and is well understood by those skilled in the art, but skill and care has been required in administering the same in order to secure the result sought and without causing the patient pain or even injury.

My improved method is to direct the lamp or light of an intensity greater than can be endured for a considerable period against the part to be treated and automatically interrupting the light at substantially regular intervals and for substantially uniform periods, thereby alternately exposing the part treated to the light and heat and permitting it to cool, the cooling periods, however, being relatively short. This interruption I preferably accomplish by means of a thermal flasher device consisting of the casing or housing 2 having an insulating block 3 therein carrying the thermostatic element 4. This thermostatic element is wound by the resistance wire 5, one end of which is connected to the binding post 6. The thermostatic element is bowed so that by its expansion it comes in contact with the contact point 7 which is connected to the binding post 8 to which one of the circuit wires 9 is connected, as shown in Fig. I.

The contact 7 is adjustable so that the flashing periods may be regulated.

With this simple arrangement the current is turned on for a predetermined period and off for a substantially predetermined period and alternate heating and cooling of the surface is secured, the lamp being cut off for a sufficient period to allow the surface to cool to a point securing the desired result in the matter of the flow of blood to and from the treated part and preventing an access of blood or congestion and preventing such overheating as would be injurious or disagreeable or painful to the patient.

Having thus described my invention, what I claim as new and desire to secure by Letters Patent is:

1. The method of administering treatments consisting of directing a lamp against

- the part to be treated, such lamp being of a heating capacity greater than can be endured on a continuous exposure and automatically interrupting the light at substantially regular intervals and for substantially uniform periods, thereby alternately exposing the part to the light and heat and permitting it to cool, the cooling periods being relatively short.
- 10 2. The method of administering treatments consisting of directing a lamp against the part to be treated, such lamp being of a heating capacity greater than can be endured on a continuous exposure and interrupting the light at intervals for substantially uniform periods, thereby alternately heating and cooling the part.
- 15 3. The method of administering treatments consisting of directing a lamp against the part to be treated, such lamp being of a heating capacity greater than can be endured on a continuous exposure and interrupting the light at intervals, thereby alter-

nately heating the part and permitting it to cool. 25

4. The method of administering treatments consisting of directing an electric lamp against the part to be treated, the lamp being in circuit with a thermal flasher whereby the current is interrupted at intervals, thereby providing an alternate heating and cooling of the part treated. 30

5. The method of administering treatments consisting of directing an electric lamp provided with a reflector against the part to be treated, and automatically interrupting the current to the lamp so that the part is alternately heated and cooled for substantially uniform periods.

In witness whereof, I have hereunto set 40
my hand and seal in the presence of two
witnesses.

ROY X. TUTTLE. [L. s.]
